UNITED STATES PATENT OFFICE.

MARSHALL O. ROBERTS, OF WASHINGTON, DISTRICT OF COLUMBIA.

DESIGN FOR A SPOON.

SPECIFICATION forming part of Design No. 22,212, dated February 14, 1893.

Application filed January 5, 1893. Serial No. 457,405. Term of patent 7 years.

To all whom it may concern:

Be it known that I, MARSHALL O. ROBERTS, residing at Washington city, in the District of Columbia, have invented and produced a new and original Design for Spoons, of which the following is a specification, reference being had to the accompanying drawing, in which the figure is a face view of the spoon.

The essential feature of my design is the configuration of the handle.

The handle A has a straight middle part a , and its upper end spread to form a flattened end a' which end tapers to a point a^2 . Upon the end a' is a figure B, which is intended to represent a miniature likeness of John Howard Payne, the author of "Home Sweet Home." The face of the handle has a floral ornamentation C, representing a running vine, the upper part of which is spread to form a wreath like border c for the figure B. Under the fig-

ure B, is a figure D which is intended to represent a dove hovering over a plane surface ornamentation E, intended to represent an inscription tablet. The figure F on the middle part of the handle is intended to represent a strain of music from "Home Sweet Home." Below the figure F is a figure G representing a song bird. The floral ornamentation C ends where the handle merges with the bowl and on such bowl is produced a figure of a homestead, which is intended to represent the homestead of John Howard Payne, the author of "Home Sweet Home."

What I claim is—

The design for a spoon substantially as herein shown and described.

MARSHALL O. ROBERTS.
